D. J. MACHOL

FILM HOLDER FOR DENTAL PURPOSES

Original Filed Feb. 18, 1922

INVENTOR
David J. Machol
BY
Edward A. Jarvis
ATTORNEY

UNITED STATES PATENT OFFICE.

DAVID J. MACHOL, OF WEST NEW BRIGHTON, NEW YORK, ASSIGNOR TO JOSEPHINE MACHOL, OF WEST NEW BRIGHTON, NEW YORK.

FILM HOLDER FOR DENTAL PURPOSES.

Application filed February 18, 1922, Serial No. 537,616. Renewed February 5, 1924.

To all whom it may concern:

Be it known that I, DAVID J. MACHOL, a citizen of the United States, residing at West New Brighton, county of Richmond, State of New York, have invented certain new and useful Improvements in Film Holders for Dental Purposes, of which the following is a full, clear, and exact description.

10 This invention relates to improvements in devices to aid in the use of the X ray as applied to the dental art. To photograph or take an X ray to obtain a picture of the condition of a tooth at its root or to obtain a picture of the condition of the gums interiorly thereof, a specially arranged film is employed which is applied to the gum at the region to be photographed. These films are usually pressed against the gum and held by the fingers or a finger of the patient while an operator manipulates the X ray machine. These films are flexible or rather yieldable being usually mounted on a lead plate so that the film can be caused to fit closely to the gum. One of the objects of 25 my invention is to provide means that will obviate the necessity of holding the films by the fingers, which is not sanitary to say the least.

30 I will now proceed to describe my invention, reference being had to the accompanying drawing, wherein:

Fig. 1 is a face view of my invention, illustrating a film in position;

35 Fig. 2 is a sectional side view illustrating my invention in use;

Fig. 3 is a side view illustrating the device under normal conditions or when not in use;

40 Fig. 4 is an enlarged fragmentary face view, looking from the left in Fig. 2;

Fig. 5 is a top plan view of the film holder;

45 Fig. 6 is an enlarged fragmentary sectional view of the lower end of the tubular member of the post;

Figs. 7 and 8 are detail views of one of the pads carried by the post; and

50 Fig. 9 is a face view illustrating a long pad, as applied to the lower end of the post, to bridge a gap between teeth.

To carry my invention into practice, I

provide a collapsible film holder that can be held between the teeth consisting of a suitable carrier having mounted thereupon means to retain a film. The carrier is arranged to be gripped by the teeth, the film being forced against the gums when the carrier is collapsed, special means being provided to automatically force the film against the gums. As herein arranged, my invention consists of a collapsible post 10 made up of the tubular member 11 slidably supporting a spindle 12. The tubular member 11 carries a spring 13 acting against the spindle 12 to force it outwardly, a pin 14 carried by the spindle engaging a slot 15 in tubular member 11, which acts to limit the outward movement of spindle 12. In this instance one end of member 11 and one end of spindle 12 carries a head 16 to which is applied a pad 17 preferably of soft rubber. Each pad 17 is removably secured to its head 17, in this instance, by a threaded stud 18 carried by a plate 19 to which it is applied the studs engaging 75 threaded openings 18^a in the heads 16. In this instance each pad is applied to its plate by means of a tongue 20 which engages a rabbet groove 21 in the plate which carries the pad. By this means, I am able 80 to renew the pads whenever necessary. The pads 17 will be of various sizes to suit different conditions. Should the device be applied at a portion of the mouth where a gap in the teeth occurs, as indicated in 85 Fig. 2, I would apply a pad long enough to bridge the gap. In this instance the gap is illustrated as occurring in the lower row of teeth; should it occur in the upper row, I would apply a long pad to the 90 spindle 12. Should the gap occur at both lower and upper rows of teeth each member 11 and 12 would be provided with a long pad. The pads may be made in various shapes to suit different conditions of 95 the teeth. To support the film 22, I provide a frame 23 provided with grooves 24 to receive the film. The film extends for some distance above the frame in order that it will bend to accommodate itself to the 100 contour of the gums, as indicated in Fig. 2. The frame 23 carrying integral ears 26

is pivotally connected as at 25 to the head 16 on the spindle 12. In this instance each ear 26 carries a downwardly extending arm 27, said arms straddling a wedge 28 carried by tubular member 11. The arms 27 carry a pin 29, which extends across the face of the wedge and which bears against the wedge when the film is forced against the gum, indicated by dotted lines 30 in Fig. 2. The device operates as follows:— Should it be necessary to take an X ray of the condition of a tooth at its root, a film 22 will be placed in the frame 23, the device being in normal condition or expanded, as indicated in Fig. 3 with the film supporting frame tilted. The patient will now be told to open his mouth after which the operator will place the device between the teeth, the film, of course, being positioned behind the teeth whether upper or lower. After the device has been inserted, the patient will close the teeth upon the pads 17 and force the spindle 12 into the tube 11, thereby compressing spring 13. This action will cause the pin 29 to ride over the inclined surface of the wedge 28, thereby forcing frame 23 and its film 22 upward. The patient will force the post members together until the pressure of the film 22 upon the gum is felt, or in other words, the patient will collapse the post members to their full extent, which action will force the film against the gum, causing it to bend to conform to the shape of the gums. The spring 13 will maintain the members 11 and 12 in expanded condition when the device is not in use; hence, it does not have to be expanded while being applied. The operator can insert or position the device in the mouth without placing his fingers in the patient's mouth, as forceps can be used to manipulate it. The tubular member 11 will preferably be provided with openings 30 in order that the inner portion of the device, as well as the outer portion can be sterilized. The films 22 which I use are well known in the dental art and are pliable so that they can be caused to conform to the contour of a gum. My device can be constructed differently than herein shown, the structure selected being illustrative of a good practicable construction.

What I desire to secure by Letters Patent is:—

1. A film holder, adapted to receive a film and insertable into the mouth, teeth engaging members, means for normally holding said members apart, and means whereby when said members are moved toward each other said film will be positioned against the gums.

2. A film holder adapted to receive a film and insertable into the mouth, teeth engaging members associated therewith, a cam

on one of said members, and an extension on said film holder adapted to engage said cam, said film holder being operable toward or away from the gums upon a closing or opening movement of the jaws, respectively. 70

3. A holder insertable into the mouth, means pivotally carried thereby to retain a film, teeth engaging members on said holder, and means associated with said teeth engaging members to operate said film retaining means when the teeth engaging members are moved. 75

4. A holder insertable into the mouth, consisting of collapsible members, a pivoted frame carried thereby to retain a film, and means carried by one of said members to move a film carried by the frame into contact with the gums, when the holder members are collapsed. 80

5. A holder insertable into the mouth 85 consisting of collapsible members, means carried by each of said members to engage the teeth of the upper and lower jaw, a movable frame carried by one of said members to retain a film, and means carried by the other member to operate the frame to force a film carried by the frame against the gums, while the holder members are being collapsed when the jaws are closed upon the same. 90

6. A holder insertable into the mouth, consisting of collapsible members, a pivoted frame carried thereby to retain a film, means carried by one of said members to move a film carried by the frame into contact 100 with the gums, when the holder members are collapsed, and means to keep said collapsible members normally separated. 95

7. A holder insertable into the mouth, consisting of collapsible members, a pivoted 105 frame carried thereby to retain a film, means carried by one of said members to move a film carried by the frame into contact with the gums, when the holder members are collapsed, and a spring to keep said collapsible members normally separated. 110

8. A film holder insertable into the mouth and a film therefor, collapsible members associated with said holder, and means whereby said film holder is moved upon a movement of said collapsible members. 115

9. A film holder insertable into the mouth and a film therefor, collapsible members associated with said film holder, and a pivoted member adapted to force the film against 120 the gums upon a collapsing movement of said collapsible members.

10. A holder insertable into the mouth consisting of collapsible members, means carried by each of said members to engage the teeth of the upper and lower jaw, a movable frame carried by one of said members to retain a film, and a wedge carried by the other member to operate the frame to force a film carried by the frame against 125 130

the gums, while the holder members are being collapsed when the jaws are closed upon the same.

11. A film holder and film therefor, insertable into the mouth, said holder adapted to have contact with the teeth during an opening or closing movement of the jaws whereby the film will be moved toward or away from the gums.

12. A mechanically operated film holder insertable into the mouth, and a teeth engaging member associated therewith, said holder being adapted for use in either side of the mouth without changing the relative positions of said holder and said teeth engaging member.

DAVID J. MACHOL.
